COMPOSITE SLAB STRUCTURE

Clarke F. Davis and John G. Brush, Westfield,
N. J., assignors to Structural Gypsum Corpora-
tion, Linden, N. J., a Corporation of Dela-
ware

Application July 28, 1930. Serial No. 471,137

5 Claims. (Cl. 108—10)

The present invention relates to assembled building units, each of which comprises a composite article of manufacture made from structural elements and precast slabs of plastic material, and to a building construction embodying the same.

In the building art it is common practice to construct a roof from purlins, girders, main roof supports or the like, and to erect therein precast slabs of gypsum so as to provide a substantially continuous roof surface. Where such purlins, girders, or other main roof supports are not so spaced as to conveniently take such slabs, it is common practice to provide sub-purlins, rails, or tees between the same and spaced at such a distance that slabs of any convenient length may be supported thereby. Obviously, the spacing of the sub-purlins, rails or tees may be such as to take any convenient length of slab.

Experience has shown that precast slabs of gypsum, either with or without metal reinforcements or fillers, and either hollow or solid, can be manufactured at a minimum cost and at maximum speed and efficiency on some kind of automatic machinery of which that shown in the patent to Ruby, #1,692,420, is a type, rather than individually by hand as heretofore.

Where slabs having projecting metal reinforcements are used in a roof deck construction, it becomes necessary and desirable to twist together the reinforcement ends of adjacent slab ends so as to form a substantially continuous truss element. While this operation is comparatively simple in itself, yet it involves considerable expense in that circumstances demand that skilled labor of a certain type perform this act, while unskilled labor may erect the slabs themselves. Thus, two types of labor, with the necessary foremen, supervisors, etc. are required with the roof slab constructions above described and they are, therefore, expensive both from the standpoint of first cost and erection.

It is among the objects of this invention, therefore, to provide a building unit which may be constructed at minimum cost and at maximum speed, and assembled and erected by only a single type of labor, and that the cheapest, unskilled class. Another important object of the invention is to provide a roof deck of maximum strength.

One aspect of the invention contemplates an assembled building unit composed of two spaced apart parallel metal structural elements holding therebetween a plurality of precast slabs

of gypsum or the like, and tie rods extending between the structural elements so that the whole may be handled as a unit. Such a composite slab may be incorporated in a building construction such as a roof deck, by laying continuous and contiguous rows thereof, the ends of the structural elements thereof resting on purlins. As an alternative method of erection, such composite units may be laid in rows spaced apart a distance equal to the length of the slabs incorporated in them, and then loose precast slabs erected between the rows of composite units, the ends of the loose slabs resting on a flange of the structural elements of the units. In either of the above erection procedures, the same type of unskilled labor may be employed to cast and assemble the slabs and units, all of which effects a material saving.

The invention further contemplates the provision of means such as a butt plate welded or otherwise secured to the structural elements of a composite slab in order to prevent the loose slabs erected according to the alternative procedure described above from slipping from between the structural elements on which they rest, where a pitched roof deck is involved, and for other purposes.

The invention further contemplates means such as a bottom plate welded or otherwise secured to the bottom of the structural elements of a composite slab or unit, said plate having a toe or finger projecting downwardly therefrom, the plate increasing the bearing surface of the units and the toe or finger being adapted to engage the upper flange of a purlin to prevent slippage of the units or rows of units in steep pitched roofs.

The invention further consists in the novel arrangement, combination and construction of parts more fully hereinafter described and shown in the accompanying drawings.

In the drawings:—

Fig. 1 is a partial plan view of a roof deck erected according to this invention.

Fig. 2 is a sectional view of Fig. 1 along the line 2—2.

Fig. 3 is an end view of Fig. 1, looking in the direction of the arrow.

Fig. 4 is a perspective view showing one method of erecting slabs according to this invention.

Fig. 5 is a perspective view of another system of erection.

Fig. 6 is a perspective view of a completed section of a roof.

Fig. 7 is a partial end view of a building construction embodying this invention.

Fig. 8 is a partial plan view of the roof deck of Fig. 7.

5 Fig. 9 is a composite fragmentary view of one end of a structural element carrying a bottom plate.

Fig. 10 is a side view of a construction using the bottom plate of Fig. 9, and

10 Fig. 11 is a perspective view of a structural element to which a butt plate is attached.

Referring now to that embodiment illustrated in Figs. 1, 2 and 3, there is shown a building unit composed of a plurality of precast slabs, one of 15 which is shown at 1 to consist of a body of plastic material such as gypsum or the like, crystallized or set with the requisite amount of water and with or without a filler such as wood chips or the like, all of which is well-known in 20 the art. This slab may preferably be made on a machine of the automatic type, of which that shown in the patent to Ruby #1,692,420 is illustrative, and as shown, contains core holes 2 and reinforcing rods 3 embedded in the lower 25 tension zone of the slab, both the core holes and the reinforcing rods being formed and placed respectively during manufacture. It is desirable to form the slab with side flanges, shown at 4, along its longitudinal edges, which, when a plurality of slabs are assembled together, spaces the main bodies thereof apart and forms with the neighboring slab a channel or groove, for 30 purposes to be more fully described hereinafter.

The series of slabs 1 are designed to be held 35 together as a unitary article of manufacture, by means of spaced apart-parallel metal structural elements of any desired configuration, each of which are shown in Fig. 3 to consist of shaped sheet metal sections 5 having an upper flange 6 and two lower flanges 7 and 8, the last two flanges extending on each side of the web thereof, and forming between flanges 6 and 7 a channel, adapted to receive the lateral ends of the individual slabs 1. If desired, the upper portion 40 of the slabs may be rabbeted to receive the flange 6 so that the upper surfaces of the slab and flange may be substantially flush. The plurality of slabs are secured between the structural elements by means of tie rods 9 extending 45 from one element 5 to the other, each rod having a head 10 at one end and tightening nut 11 on the other.

The tie rods 9 may be located at any convenient 50 place in the assembled unit, and in Fig. 2 they are shown as passing beyond the side of the slab as in the case of the left-hand-rod, between the slabs as in the case of the middle rod, and through a core hole in the slab as is the case of the right-hand rod. The length of the composite 55 slab or building unit will determine the most expeditious number and location of the rods. Where the rods pass between slabs, they may be thoroughly protected from weather and fire 60 by the use of soft grouting filled into the grooves between the slabs. The end rods are likewise protected and embedded by grouting poured between the unit ends after erection.

Obviously the structural elements may be of 65 any desired length, depending upon the distance between centers of the purlins upon which they rest. In some instances it will be found that for certain lengths of structural elements it will be necessary to longitudinally split a slab 70 in order to fit the same thereto. Such a split

slab or slab portion is shown at 12 at the left-hand end of Fig. 2. This presents no particular problem inasmuch as gypsum slabs may be sawed without difficulty.

In erecting building units as above constructed, the units having been assembled at the factory, they are placed in position on the purlins 13 which may be I beams as in Fig. 6 or channels as in Fig. 7, in spaced apart rows. Such rows are shown as a skeleton structure in 80 Fig. 4. In that method of erection, the units are spaced apart a distance equal to the length of an individual slab. Upon placing the units, loose slabs 14 of the same type may then be erected between the units, the slab ends resting 85 on the flanges 8 of the neighboring units, as shown in Fig. 3. Such a system makes use of but one type of precast slab, both for the assembled units and for intermediate loose rows of 90 slabs.

Where such a system of loose and assembled 95 slabs are used on a steep pitched roof deck, it may be found desirable to provide means to prevent accidental displacement of the loose rows of 100 slabs. Such means are shown in Figs. 7, 8 and 11 to consist of a butt plate 15 welded or otherwise secured to one end of each of the structural elements in the unit nearest the eaves, the structural element 16 in these figures being a solid rolled member. The corner of a loose slab abuts 105 this plate, which effectively prevents slippage or accidental displacement. It is to be noted that the outside tie rod 9 (left-hand end of Fig. 2) prevents any tendency of the assembled slabs to move. Where desired, the butt plate 15 may be 110 provided with an elongated slot 17, which serves to accommodate means such as a bolt or the like for securing a nailing strip thereto, to which a gutter or the like may be fastened. Obviously, 115 where desirable, the bottom flange of a structural element may be slit back from the end parallel with the web thereof and that portion turned up at right angle to the flange, to serve the same purpose as the butt plate.

Figs. 7, 9 and 10 illustrate means in a steep 120 pitched roof deck to prevent slippage of each assembled unit or an entire row thereof. Such means comprise a bottom plate 18 welded or otherwise secured to the bottom of the one end of 125 the structural elements 16 of a unit, in an offset manner, that is, so as to project beyond the end of the element to which it is attached. The plate 18 is provided with a punched-out toe or finger 19 which is adapted to engage the upper 130 flange of a purlin 13 as shown in Figs. 7 and 10. Thus, each assembled unit is independently held in proper place. Obviously, by deforming the toe 19 under the flange of the purlin, the units may be positively and effectively secured thereto, both 135 against longitudinal movement and upward movement. This is often desirable.

The plate 18 being offset from one end of the element 16, provides an increased bearing surface for the adjacent end of the neighboring element as shown in Fig. 9, which is sometimes desirable, particularly where the purlins constitute channels as at 13 (Fig. 7) and the top flange thereof is not as wide as in the case of the I purlins of Fig. 2.

In some instances, it may be found desirable 140 to punch out the toe or finger 19 from the bottom flange of the structural element itself rather than form this part from the bottom plate.

As a modified system of erecting such assembled 145 building units, reference is made to the

5 skeleton showing of Fig. 5. Here two structural elements are shown, one at 20 substantially similar to that shown at 5 in Fig. 3, except that the bottom thickness of metal is in substantially a single plane. Its companion element is shown at 21 to consist of an ordinary channel, spaced from its neighbor by the heel 22 of the element 21. This space between elements 20 and 21 may be filled with grouting after erection. It will 10 thus be seen that the construction of Figs. 5 and 6 consist of contiguous rows of assembled units, each unit composed of a series of precast slabs tied together with rods 9 as before. Obviously the bottom plate of Figs. 9 and 10 may be used 15 with the above described pair of structural elements for the purpose as hereinbefore specified.

From the above, it will be apparent that an assembled building unit has been provided, the individual slabs of which may be manufactured 20 with minimum ease and cheapness in quantities and which thus assures a uniformity of production, such slabs being of a type which makes them readily adapted to be assembled by cheap factory labor and incorporated in a building construction such as a roof deck, either as assembled units or as loose slabs. This circumstance makes it possible to provide a slab of any desired dimension so that the size of the ultimate units 25 may be varied at will.

30 It has been proven that the herein-described structural elements may be manufactured to give the requisite strength at a lower cost than the usual rails or T's heretofore used and that the total cost of manufacture and erection of the 35 slabs as heretofore used, far exceeds the system herein described.

Obviously, the building units of a row may be tied together by any desired means, so as to constitute in effect but a single continuous element. 40 Such a construction has the advantage of added rigidity over one where there is no positive connection between units.

Such a roof deck may, of course, be covered 45 with any waterproof or weather-resisting material such as building or roofing paper, tar, all of which is well known in the art.

While the invention has been described with 50 reference to hollow precast slabs of gypsum, yet obviously the invention is not to be limited thereto as slabs of any desired design may be used, it being a part of this invention to make a distinction between a composite slab which is poured between structural elements and one which is assembled from a plurality of precast 55 slabs. Again, it is to be understood that the invention is not concerned with any particular kind of structural element as this may take any form most suited to the particular circumstances.

The invention is therefore to be construed broadly and limited only by the scope of the claims.

I claim:

1. A building construction comprising purlins, a series of spaced apart assembled building units supported thereon, each unit including a plurality of precast slabs tied together between structural elements, the structural elements resting upon the purlins, each of the structural elements having a base flange extending on each side of the web, and other precast slabs between the units, said slabs being supported at each end upon the base flange of a structural element of an assembled unit. 80

2. A building construction comprising purlins, a series of structural elements having base flanges extending on each side of their webs and resting upon the purlins, a plurality of precast slabs between the elements and having their ends resting on the base flanges thereof, 95 tie means for each two elements, the thus tied pairs of elements being spaced apart the length of a precast slab, and additional precast slabs between the spaced apart pairs of elements and resting on their base flanges. 100

3. A building construction comprising purlins, building units supported on said purlins and including structural elements, and means projecting from beneath a structural element and engaged with a purlin to prevent accidental displacement of the units, said means comprising a plate secured to the bottom of the structural element and projecting beyond the end thereof and having a toe engaging the purlin. 105

4. A building construction comprising purlins, a series of spaced apart assembled building units supported thereon, each unit comprising spaced apart structural elements, loose precast slabs supported between the rows of assembled units and resting upon flanges of the structural elements, and means carried by the structural elements to prevent accidental displacement of the loose slabs, said means comprising a butt plate secured to the end of the structural elements. 110

5. A building construction comprising purlins, a series of spaced apart assembled building units supported thereon, each unit comprising spaced apart structural elements, loose precast slabs supported between the rows of assembled units and resting upon flanges of the structural elements, and means carried by the structural elements to prevent accidental displacement of the loose slabs, said means comprising a butt plate secured to the end of the structural elements 115 and having an elongated slot therein. 120

CLARKE F. DAVIS.

JOHN G. BRUSH.
